UNITED STATES PATENT OFFICE.

EDWARD J. JACKOBOICE, OF GRAND RAPIDS, MICHIGAN.

ROAD SCRAPER.

Application filed March 21, 1923. Serial No. 626,564.

To all whom it may concern:

Be it known that I, EDWARD J. JACKOBOICE, a citizen of the United States, residing at Grand Rapids, in the county of Kent and State of Michigan, have invented new and useful Improvements in Road Scrapers, of which the following is a specification.

The present invention relates to road scrapers; and its object is to provide a road scraper having improved means for yieldingly holding the scraper blade in contact with the surface of the road being operated on; and further, to provide such a scraper having improved means for changing the angle of the scraper blade relatively to the direction of the machine's travel over the road; and further, to provide such a scraper having improved means for raising and lowering the scraper blade; and further, to provide improved more specific means for carrying out said objects.

These and any other objects hereinafter appearing are attained by, and the invention finds preferable embodiment in, the road scraper particularly described in the body of this specification and illustrated by the accompanying drawings, in which:—

Figure 1 is a top plan view of a portion of a vehicle and a road scraper mounted thereon;

Figure 2 is a left-hand side view thereof, the scraper blade of the machine being shown at right angles to the vehicle in this view;

Figure 3 is a side view of part of the mechanism for tilting the scraper blade;

Figure 4 is a side view of an adjustable bearing block and connected parts;

Figure 5 is a side view of a non-adjustable bearing block and connected parts;

Figure 6 is a front edge view of the same, connected parts being sectioned on line 6—6 of Figure 5; and

Figure 7 is a rear view of a portion of the scraper blade and connected parts.

In the embodiment of the invention chosen for illustration by the drawings and for detailed description in the body of this specification, the road scraper mechanism is mounted on a vehicle—a motor truck—having the frame 1 and rear or traction wheels 2. Bearing blocks 3 carried by the frame adjacent its opposite sides respectively, have vertically-disposed bearings 4 in which the spindles 5 of the bearing members 6 may rock and may also move verti-

cally to fixed clamped positions, being thus clamped in position by the screw bolts 7. These bearing members 6 have horizontally-disposed bearings 8 in which rocks a horizontally-disposed shaft 9 carrying the scraper blade 10. This scraper blade is thus carried by means of collars 11 turnably adjustable to fixed positions on the shaft by clamping screws 12, the scraper blade being supported on the collars by means of its upright posts 13 rockably mounted on the collars at 14. The scraper blade is yieldingly held relatively to the collars by springs 15, 16 coiled around rods 17 carried by the collars and passing freely through openings 18 in the scraper blade, these springs pressing against the opposite sides respectively of the scraper blade, their tension being adjustable by the nuts 19 threaded on said rods. 75 It will be seen that the scraper blade is thus held yieldingly balanced by the springs 15 and 16 and may thus yield forwardly or rearwardly in its contact with the surface 20 of the road being operated on.

The scraper blade may be tilted to a desired angle about the axis of the shaft 9 by rocking the shaft in its bearings 8 by suitable means, as by turning the upright shaft 21 (provided with a suitable hand wheel not shown), journaled at 22 on the vehicle's frame and having a worm 23 meshing with a toothed segment 24 pivoted at 25 on the frame and pivoted eccentrically at 26 to a connecting rod 27 whose rear end is pivoted at 28 on an arm 29 of a sleeve 30 on the shaft 9, said sleeve being adjustable by its clamping screws 31 in fixed positions on the shaft.

In order that the angle between the scraper blade and the travel of the vehicle over the road (the direction of such travel being indicated by the arrow in Figure 1) may be changed as desired, one or both of the bearing blocks 3 may be moved horizontally on the frame of the vehicle—i. e., either forwardly or rearwardly—the shaft 9 in such movement sliding in its bearings 8; and these bearing blocks 3 may, when thus moved, be secured to the frame by their attaching bolts 32 passing through other openings 33 in the frame: or, as shown, one or both of said bearing blocks may be slid forwardly or rearwardly on the frame by the screw 34 threaded on the vehicle's frame and engaging the bearing block at 35 and by its turning movement sliding the

bearing block along the frame in bearings afforded by the frame's slots 36 through which pass the bolts 32 which secure the bearing block slidably to the frame. The 5 scraper blade 10 may be bodily raised or lowered, together with the shaft 9 and parts carried thereby, by the vertical movement of the spindles 5 of the bearing members 6 in the vertical bearings 4 of bearing blocks 10, these spindles being thereupon secured in position by tightening the clamping bolts 7. The connecting rod 27 may be lengthened and shortened as required by turning its turnbuckle 40, and the brace 41 may be 15 similarly adjusted as to length by its slotted splice portion 42, as illustrated in Figure 1.

From the foregoing description, the operations of my road scraper will be readily understood, viz: The scraper blade may be 20 bodily raised and lowered by means of the spindles 5 vertically adjustable in the bearings 4; the scraper blade may be inclined at a desired angle to the direction of the vehicle's travel by moving one or both of the 25 bearing blocks 3; the scraper blade may be tilted on the axis of the shaft 9 by the worm and segment mechanism connected to the sleeve 30; this sleeve and also the collars 30 11 may be adjusted to desired turned positions on the shaft 9 by clamping screws 31 and 12; the scraper blade is yieldingly balanced against rearward and forward turning movement on its pivotal mounting 14 by the springs 15 and 16, whose tension 35 is adjustable by the nut 19.

The invention being intended to be pointed out in the claims, is not to be limited to or by details of construction of the particular embodiment thereof illustrated by the drawings 40 or hereinbefore described or shown.

I claim:

1. In combination with a vehicle having a frame, a road scraper comprising: a horizontally-disposed shaft rockable in bearings 45 on said frame; a scraper blade carried by the shaft rockably on a horizontally-disposed axis; springs carried by the shaft and pressing against the opposite sides respectively of the scraper blade.

2. In combination with a vehicle having a frame, a road scraper comprising: a horizontally-disposed shaft rockable in bearings on said frame; collars carried by the shaft; a scraper blade carried by the collars rockably on a horizontally-disposed axis; springs 55 carried by the collars and pressing against the opposite sides respectively of the scraper blade.

3. In combination with a vehicle having a frame, a road scraper comprising: a horizontally-disposed shaft rockable in bearings on said frame; collars carried by the shaft 60 adjustably to fixed turned positions thereon; a scraper blade carried by the collars rockably on a horizontally-disposed axis; springs

carried by the collars and pressing against the opposite sides respectively of the scraper blade.

4. In combination with a vehicle having a frame, a road scraper comprising: a horizontally-disposed shaft rockable in bearings on said frame; a scraper blade carried by the shaft rockably on a horizontally-disposed axis; springs carried by the shaft and pressing against the opposite sides respectively of the scraper blade; means for rocking the shaft to fixed positions. 70

5. In combination with a vehicle having a frame, a road scraper comprising: a horizontally-disposed shaft rockable in bearings on said frame; a scraper blade carried by the shaft rockably on a horizontally-disposed axis; springs carried by the shaft and pressing against the opposite sides respectively of the scraper blade; a sleeve carried by the shaft adjustably to fixed turned positions thereon; means extending between said frame and the sleeve for rocking the shaft to fixed positions. 80

6. In combination with a vehicle having a frame, a road scraper comprising: a horizontally-disposed shaft rockable in bearings on said frame; collars carried by the shaft; a scraper blade carried by the collars rockably on a horizontally-disposed axis; rods 95 carried by the collars and extending through openings in the scraper blade; springs coiled about the rods and pressing against the opposite sides respectively of the scraper blade. 100

7. In combination with a vehicle having a frame, a road scraper comprising: a horizontally-disposed shaft rockable in bearings on said frame; collars carried by the shaft; a scraper blade carried by the collars rockably on a horizontally-disposed axis; rods carried by the collars and extending through openings in the scraper blade; springs coiled about the rods and pressing against the opposite sides respectively of the scraper 105 blade; means for adjusting the tension of the springs. 110

8. In combination with a vehicle having a frame, a road scraper comprising: a horizontally-disposed shaft rockable in bearings on said frame; a scraper blade carried by the shaft rockably on a horizontally-disposed axis; springs carried by the shaft and pressing against the opposite sides respectively of the scraper blade; means for adjusting the tension of the springs. 115

9. In combination with a vehicle having a frame, a road scraper comprising: bearing blocks carried by the frame adjacent its opposite sides respectively and having vertically-disposed bearings; bearing members rockably mounted in said bearings and having horizontally-disposed bearings; a horizontally-disposed shaft rockable in said last-mentioned bearings; a scraper blade 120 125 130 135 140 145 150 155 160 165 170 175 180

carried by the shaft rockably on a horizontally-disposed axis; springs carried by the shaft and pressing against the scraper blade.

10. In combination with a vehicle having a frame, a road scraper comprising: bearing blocks carried by the frame adjacent its opposite sides respectively and having vertically-disposed bearings, at least one of said blocks being horizontally adjustable to fixed positions on said frame; bearing members rockably mounted in said bearings and having horizontally-disposed bearings; a horizontally-disposed shaft rockable in said last-mentioned bearings; a scraper blade carried by the shaft rockably on a horizontally-disposed axis; springs carried by the shaft and pressing against the scraper blade.

11. In combination with a vehicle having a frame, a road scraper comprising: a horizontally-disposed shaft rockable in bearings on said frame; collars carried by the shaft; a scraper blade carried by the collars rockably on a horizontally-disposed axis; rods carried by the collars and extending through openings in the scraper blade; springs coiled about the rods and pressing against the scraper blade.

12. In combination with a vehicle having a frame, a road scraper comprising: bearing blocks carried by the frame adjacent its opposite sides respectively and having vertically-disposed bearings; bearing members vertically-movable to fixed positions in said bearings and having horizontally-disposed bearings; a horizontally-disposed shaft rockable in said last-mentioned bearings; a scraper blade carried by the shaft rockably on a horizontally-disposed axis; springs carried by the shaft and pressing against the scraper blade.

13. In combination with a vehicle having a frame, a road scraper comprising: bearing blocks carried by the frame adjacent its opposite sides respectively and having verti-

cally-disposed bearings; bearing members rockable and vertically-movable to fixed positions in said bearings and having horizontally-disposed bearings; a horizontally-disposed shaft rockable in said last-mentioned bearings; a scraper blade carried by the shaft rockably on a horizontally-disposed axis; springs carried by the shaft and pressing against the scraper blade.

14. In combination with a vehicle having a frame, a road scraper comprising: bearing blocks carried by the frame adjacent its opposite sides respectively and having vertically-disposed bearings, at least one of said blocks being horizontally adjustable to fixed positions on said frame; bearing members rockably mounted in said bearings and having horizontally-disposed bearings; a horizontally-disposed shaft rockable in the bearings of said members; collars carried by the shaft adjustably to fixed turned positions thereon; a scraper blade carried by the collars rockably on a horizontally-disposed axis; springs carried by the collars and pressing against the opposite sides respectively of the scraper blade; means extending between said frame and the shaft for rocking the shaft to fixed positions.

15. In combination with a vehicle having a frame, a road scraper comprising: a horizontally-disposed shaft rockable in bearings on the frame and having a radially-extending arm; a scraper blade carried by the shaft; a worm rotatably mounted on the frame; a toothed segment rotatably mounted on the frame and meshing with the worm; a rod pivotally connected to the segment eccentrically thereof and to the arm of the shaft for rocking the shaft by the turning movement of the worm.

In testimony whereof I have hereunto set my hand at Grand Rapids, Michigan, this 19th day of March, 1928.

EDWARD J. JACKOBOICE.
